US00D494701S1

(12) **United States Design Patent** (10) Patent No.: **US D494,701 S**
Campbell (45) Date of Patent: **** Aug. 17, 2004**

(54) **LIGHT FIXTURE**

(75) Inventor: **Wayne Douglas Campbell**, Kitchener (CA)

(73) Assignee: **Canlyte Inc.**, Ontario (CA)

(**) Term: **14 Years**

(21) Appl. No.: **29/182,766**

(22) Filed: **May 30, 2003**

(51) **LOC (7) Cl.** **26-03**

(52) **U.S. Cl.** **D26/85**

(58) **Field of Search** D26/72, 80-92; 362/147, 404-408, 426, 432
